Primary Examiner — Susan Bennett Hattan*Assistant Examiner* — Marie Fast Horse(74) *Attorney, Agent, or Firm* — Baker & McKenzie LLP(57) **CLAIM**

The ornamental design for a ceiling fan light, as shown and described.

DESCRIPTION

FIG. 1 is a perspective view of a ceiling fan light in accordance with my design;

FIG. 2 is an enlarged perspective view of the ceiling fan light in accordance with my design;

FIG. 3 is an enlarged bottom plan view of the ceiling fan light in accordance with my design;

FIG. 4 is an enlarged front side view of the ceiling fan light in accordance with my design, the rear side being identical thereto; and,

FIG. 5 is an enlarged left-side view of the ceiling fan light in accordance with my design, the opposite side being identical thereto.

The broken-line disclosure of elements is understood to represent portions of the article in which the design is embodied, but which form no part of the claimed design.

1 Claim, 3 Drawing Sheets(56)
